UNITED STATES PATENT OFFICE.

JOHN V. WELLS, OF BRADDOCK, PENNSYLVANIA.

TRIPLE VALVE.

SPECIFICATION forming part of Letters Patent No. 753,019, dated February 23, 1904.

Application filed January 3, 1903. Serial No. 137,650. (No model.)

To all whom it may concern:

Be it known that I, JOHN V. WELLS, a citizen of the United States, and a resident of Brad-
dock, in the county of Allegheny and State of
Pennsylvania, have invented a new and Im-
proved Triple Valve, of which the following is
a full, clear, and exact description.

This invention relates to a triple valve which
is applicable to the ordinary fluid-pressure
brake apparatus, operating the same as the
usual triple valve and which also is capable of
additional functions in that an application of
the brakes may be made not only by a train-line
reduction, but by a train-line increase.

The invention has a certain reference to the
organism disclosed in my prior patent, No.
620,201, dated February 28, 1899, but differs
therefrom principally in that the present valve
may be applied to the ordinary air-brake ap-
paratus, making both a service and an emer-
gency application by train-line decrease inde-
pendently of application by train-line increase.
The valve here shown is especially adapted to
be used with the brake-valve shown in my co-
pending application, Serial No. 137,651, filed
January 3, 1903.

This specification is an exact description of
one example of my invention, while the claims
define the actual scope thereof.

Reference is to be had to the accompanying
drawings, forming a part of this specification,
in which similar characters of reference indi-
cate corresponding parts in all the views.

Figure 1 is a longitudinal section of the
valve on the line 1-1 of Fig. 2, showing it fas-
tened to the auxiliary reservoir and illustrat-
ing the parts in the position which they as-
sume upon a service application by a train-
line decrease. Fig. 2 is an elevational view
looking toward the auxiliary-reservoir end of
the valve, this view showing the valve with
the cap at this end removed. Fig. 3 is a sec-
tion on the line 3-3 of Fig. 1. Fig. 4 is a bot-
tom plan view of the valve with a train-line
cap removed. Fig. 5 is a bottom plan view
of the slide-valve. Fig. 6 is a diagram illus-
trating the relative position of the ports upon
the release position. Fig. 7 is a diagram illus-
trating the relative position of the ports upon
an application by a train-line increase. Fig.

8 is a diagram illustrating the position of the
ports during the service application upon a
train-line decrease. Fig. 9 is a diagram show-
ing the relative position of the ports upon an
emergency application upon a train-line de-
crease. Fig. 10 is a diagram showing the rela-
tive position of the ports when on lap after
an application by train-line increase, and Fig.
11 is a diagram showing the relative positions
of the ports when on lap after an application
by train-line decrease.

A indicates the main casing or body of the
valve, in which is formed the cylinder or pis-
ton cavity E and the slide-valve cavity B',
having at its bottom the square seat B² es-
sentially of the usual construction.

G indicates the train-line cap, which is fas-
tened to the main case A and virtually forms
a part thereof, and F indicates the drain cup
or cap, which is fastened to the end of the
body A.

b indicates the train-line connection, which
passes into the body of the valve and commu-
nicates with the two ports d and e, said ports
d and e running to the valve-seat B² and also
communicating with a cavity G' in the cap G.

h indicates the exhaust-port, which passes
from the seat B² in transverse line with a port
f to the atmosphere.

a indicates a passage extending from the
passage b into the cap G and communicating
with the cavity E by means of ports F.

K indicates the auxiliary reservoir, which
communicates with the slide-valve cavity B'
by way of a port or ports c in the casing P,
which will be fully described hereinafter.

L indicates the brake-cylinder connection,
and this communicates with two ports f and
g in the main casing A, said ports f and g
leading to the valve-seat B².

B indicates the slide-valve, which is fitted
to the seat B² and which is formed with a main
cavity j, communicating with an L-shaped
orifice or port i, opening at the bottom of the
valve B. At its other end the cavity j com-
municates with a cavity B³ in the slide-valve,
and in this cavity is mounted a check-valve Q,
this valve Q being pressed to its seat by a
spring Q', bearing between the valve and a
plug Q², fastened in the cavity B³.

- k* indicates a port which is formed in the bottom of the slide-valve B and communicates with the cavity B'. (See Figs. 3 and 5.) The valve Q closes communication from the port 5 *k* to the cavity *j*, but opens to permit free communication from the cavity *j* to the port *k*.
- l* indicates a groove which passes transversely across the face of the valve B and is adapted to connect the port *f* with the exhaust-port, to be hereinafter described, when the parts are in release position.
- o* indicates a port or port-groove which is formed in the side of the slide-valve B adjacent to the auxiliary-reservoir end, and *n* indicates a port adjacent to the port *o* and communicating with the cavity B', said port *n* opening at the auxiliary-reservoir end of the slide-valve B. The ports *o* and *n* are adapted to register with the brake-cylinder port *g*, respectively, upon service and emergency applications by train-line reduction, all of which will be fully set forth hereinafter.
- D indicates the piston, which works in the cavity E, and C indicates the stem fastened 25 to the piston and joined to the slide-valve B.
- C' indicates the usual spring for pressing down the parts C and B.
- J indicates an annular tubular cushion which is placed in the right-hand end of the cavity 30 E and is perforated, as shown, this cushion J being carried on a metallic rim J' and the perforations permitting any pressure leaking past the piston D to enter into the tubular cushion J, thus expanding the same. Connected to 35 the piston D is a stem D', which projects into the cap F.
- I² indicates a spring which bears between a shoulder D² on the stem D' and the inner end I³ of a cylindrical case I, which is movable 40 freely in the cap F and has fastened in its inner end a sleeve I⁴. The sleeve I⁴ has a flange I⁵, which bears against the inner face of the cap F and limits the leftward movement of the parts I and I⁴.
- I⁶ indicates an expansive spring which presses between the inner wall of the cap F and a flange I⁷ on the left-hand end of the casting I, this spring I⁶ holding the parts I and I⁴ in the position shown in Fig. 1.
- 50 Encircling the stem D' and the spring I² is a sleeve I⁸, this sleeve having an exterior flange I⁹, limiting the rightward movement of the sleeve I⁸ by contact with the sleeve I⁴.
- I¹¹ indicates a spring which bears between 55 the inner end I³ of the case I and the flange I⁹ and pushes the sleeve I⁸ into contact with the sleeve I⁴.
- The casing I is formed with a number of orifices I¹², which permit the free passage of 60 the pressure through the cap F.
- In the passage *a* is placed a check-valve H, which opens toward the train-line connection and is held normally seated by a spring H'.
- H² indicates a port which is formed in the 65 valve H, this port being always open, irre-

spective of the position of the valve, the purpose of which arrangement will be hereinafter set forth.

The before-mentioned cavity G' carries a check-valve N, which opens into the cavity 70 from the train-line connection *b*. This cavity G' also carries a valve O, the stem of which has sliding connection with the valve N, and between these valves N and O an expansive springs N' bears, this spring tending normally 75 to seat the valve N. A hollow plug O² is screwed or otherwise fastened into the cap G and covers a chamber b', formed in said cap. In this chamber is located a diaphragm O⁵, which is joined to the stem of the valve O and 80 to a collar O⁴, these parts O⁵ and O⁴ forming the bottom of the chamber b'. The disk or collar O⁴ has a rod O' projected downward therefrom into the tubular plug O², and O³ indicates an expansive spring pressing upward on 85 the stem O', this spring tending to open the valve O.

O' indicates a nut for regulating the tension of the spring O³.

As indicated best in Fig. 2, a passage b² extends from the chamber b' upward past the seat B' and discharges into the slide-valve cavity B'.

P indicates a cap which is fastened to the auxiliary-reservoir end of the main casing A 95 and has a central opening B⁴ communicating with the slide-valve cavity B'. In this cap P a cup-leather piston P² works, said piston having a stem P', around which is encircled a spring P³, this spring pressing against the 100 piston P² and a regulating-nut P⁵. Said piston P² has a second stem or stud P⁴, which projects through the orifice B⁴ into the valve-cavity B' in position to strike the slide-valve. Formed in the cap P is a port p, which leads 105 into the main casing A and communicates with the port g.

Such being the construction and organization of the valve, its operation may be traced as follows: Assuming that the auxiliary reservoir and brake-cylinder are exhausted of pressure and that the auxiliary reservoir is to be charged, upon charging the train-line the pressure will pass into the passage b and also into the cap F, this latter movement of the 110 pressure occurring through the port *a* and the vent H² of the valve H. The spring I' will previously have thrown the piston D rightward until the cushion J strikes the end of the cavity E, and the train-line pressure 115 will therefore merely bear against the left face of the piston D. Simultaneously with this the train-line pressure on entering the port b will knock down the valve N and the spring O³ will previously have raised the 120 valve O, thus opening communication between the passage b and the chamber b'. From this chamber b' the pressure will pass through the passage b² into the cavity B' and charge the auxiliary reservoir through the 125 130

port *c*. The vent *H*² and the passages in the valve *N* are so proportioned that a slightly greater volume of pressure passes through the vent *H*² than past the valve *N*. This excess pressure is just sufficient to move the slide-valve to release position upon increasing train-line pressure after service application by train-line decrease; but the passages are so gaged relatively as to prevent compressing the spring *I*⁶, and thus moving the slide-valve farther to the right than the release position shown in Fig. 6. This undesirable rightward movement would occur when releasing after an application by train-line reduction if the open passages in the port *a*, leading to the left of the piston, were of much greater area than the port leading from the chamber *b*' to the chamber *B*'. The spring *O*³ should previously have been adjusted according to the pressure which it is desired to maintain in the auxiliary reservoir. Assuming that seventy pounds is to be carried in the auxiliary reservoir, when there is less than this pressure on top of the diaphragm *O*³ the spring *O*³ will open the valve *O*; but the instant that seventy pounds enters the chamber *b*' and from thence into the auxiliary the diaphragm *O*⁵ will be thrown down, and the valve *O* will then be closed. In this connection it will be observed that should any of the pressure leak out of the auxiliary reservoir this will be instantly replenished from the train-line pressure, which is maintained at the working pressure—say seventy pounds or more when in running position—or service application by increase of train-line pressure. Upon application of the brakes by an increase of the train-line pressure this pressure is caused to enter directly into the brake-cylinder without affecting in any way the auxiliary-reservoir pressure. Therefore upon increasing the pressure in the train-line connection *b* the cushion *J* will be compressed and the piston *D* thrown to the end of its rightward movement. The various ports will assume the relative position indicated in Fig. 7—*i. e.*, the enlarged portion *i* of the cavity *j* will bridge the ports *e* and *f*. The increased pressure from the train-line will then blow through the ports *e* *i* *f* into the brake-cylinder connection *L*. As the train-line pressure is communicated to the brake-cylinder, such pressure also enters the passage *p* and passes to the cap *P*, throwing the stem *P*⁴ to the left, as in Fig. 1, and moving the slide-valve *B* to lap position or that shown in Fig. 10. This operation occurs when a certain predetermined pressure has passed into the brake-cylinder, and it is dependent upon the relative areas of the parts *P*² and *D* and the adjustment of the spring *P*³. This cap *P* and its appurtenant parts therefore act automatically to limit the pressure which may be thrown into the brake-cylinder upon an increase in the train-line pressure, since when this pressure has been attained the stem *P*⁴ pushes the slide-valve to the lap position shown in Fig. 10. The slide-valve *B* may therefore be moved to lap position after an application for brakes on the train-line increase either automatically by the action of the device *P* and its appurtenant parts or by reducing the train-line pressure. In the lap position illustrated in Fig. 10 all of the ports are blanked excepting the ports *e* and *i*, and communication here has no effect owing to the blanking of the port *k*. To release the brakes, the train-line pressure should be reduced, thus causing the groove *l* to register with the ports *f* and *h*, as illustrated in Fig. 6, and thereupon a passage will be provided from the brake-cylinder connection *L* through the ports *f*, *l*, and *h* and thereby to the atmosphere.

In connection with the above-described operations of application by train-line increase, movement to lap position, and movement to release position let the following examples of pressures be assumed: Supposing that seventy pounds is the equalizing or normal pressure in the train-pipe and that fifty pounds is the pressure to which the brake-levers are set, or, in other words, the normal service-application pressure, when the slide-valve is thrown into the position shown diagrammatically in Fig. 7 the pressure from the train-line will blow into the brake-cylinder and also into the plug *P*, where working with the spring *P*³ the piston *P*² will be thrown into the position shown in Fig. 1, and the slide-valve *B* will be automatically moved to the lap position indicated in Fig. 10. The valve *B* also moves automatically to lap position, as shown in Fig. 10, when all train-line pressure in excess of the amount necessary to move the cavity *i* into communication with the ports *e* and *f* has expanded into the brake-cylinder. To release the brakes when applied as above, it is necessary to further reduce the train-line to return it to its normal or working pressure of seventy pounds.

The above-described operations respecting application by train-line increase are in principle the same as in my prior patent referred to herein. It will be observed in this connection that the auxiliary-reservoir pressure is always maintained irrespective of the above-described applications and releases of the brakes, this being effected through the medium of the passages *b*' and *b*² and the automatically-acting feed-valve *O* and its appurtenant parts.

To effect a service application of the brakes by a train-line reduction and using the auxiliary pressure after the ordinary manner of operating fluid-pressure brakes, the train-line pressure should be reduced sufficiently to throw the parts into the position shown diagrammatically in Fig. 8—that is to say, to place the port-groove *o* in communication with the brake-cylinder port *g*, blanking the other ports and allowing the auxiliary-reservoir

pressure to pass into the brake-cylinder connection L. To effect an emergency application, the train-line pressure should be still further reduced, thus bringing the port k into communication with the port f, the port i into communication with the port d, and the port n into communication with the port g, as shown in Fig. 9. The pressure from the train-pipe will then blow through the port d into the cavity j, unseat the valve Q, and blow into the brake-cylinder through the ports k and f. Simultaneously the auxiliary-reservoir pressure will pass through the port n into the port g. The slide-valve goes on lap after a train-line decrease by the reduction of the auxiliary-reservoir pressure caused by its expansion into the brake-cylinder. This occurs only when the train-line pressure is in excess of the pressure at which the auxiliary reservoir will equalize when fully expanded into the brake-cylinder. Any train-line reduction below that would tend to force the piston firmly against the gasket on the cap F at the left of the piston. This lap position is indicated diagrammatically in Fig. 11, in which it will be seen that all of the ports are blanked except the ports d and i and that owing to the blanking of the port k the communication between the ports d and i has no effect. To release the brakes, the slide-valve should be moved from the position indicated in Fig. 11 to that indicated in Fig. 6, which places the ports f, l, and h in communication and exhausts the brake-cylinder pressure into the atmosphere.

In addition to the functions referred to above, the piston P² and its appurtenances perform the function of equalizing the action of a series of triples the same as described in my prior patent hereinbefore referred to.

During the various operations described the springs I⁶, I¹¹, and I² operate to restrain the movement of the slide-valve until overcome by superior force of air-pressure, the spring I⁶ resists the piston movement to application by train-line increase, the spring I² resists the piston movement to service application by train-line decrease, (the position shown in Fig. 1,) and then both springs I² and I¹¹ come into action to resist the piston movement to emergency application by train-line decrease. It will therefore be seen that by means of this triple valve the brakes may be applied at any desired time by increasing the train-line pressure without disturbing the auxiliary reservoir. Also the brakes may be applied at any time by reducing the train-line pressure to effect either a service or an emergency application. This adapts the triple valve to the ordinary brake apparatus, and at the same time it enables it to perform additional functions.

Various changes in the form, proportion, and minor details of my invention may be resorted to at will without departing from the

spirit and scope thereof, and hence I consider myself entitled to all such variations as may lie within the intent of my claims.

Having thus described my invention, I claim as new and desire to secure by Letters Patent—

1. A triple valve comprising a casing having train-line, auxiliary and brake cylinder connections, and valve devices in the casing, said devices including a slide-valve having port-openings capable of establishing communication between the train-line and brake-cylinder connections, to effect a brake application, said slide-valve also having two additional port-openings capable each of establishing communication between the auxiliary and brake cylinder respectively, to effect service and emergency brake applications. 70

2. A triple valve comprising a casing having train-line, auxiliary and brake cylinder connections, and valve devices in the casing, said devices including a slide-valve having port-openings capable of establishing communication between the train-line and brake-cylinder connections, to effect a brake application, said slide-valve also having two additional port-openings capable each of establishing communication between the auxiliary and brake cylinder respectively, to effect service and emergency brake applications, the ports of said valve devices also establishing communication between the train-line and brake-cylinder connections upon the aforesaid emergency-brake application, whereby to reinforce the auxiliary pressure from the train-line. 95

3. A triple valve comprising a casing having train-line, auxiliary and brake cylinder connections, valve devices in the casing, said devices having ports capable of establishing communication between the train-line and brake-cylinder connections, to effect a brake application, and also having two additional ports capable each of establishing communication between the auxiliary and brake cylinder, respectively to effect service and emergency brake applications, and three springs acting with said valve devices, the one spring resisting movement to train-line brake-cylinder communication, the second spring resisting movement to auxiliary-brake-cylinder service communication, and the second and third springs resisting movement to auxiliary-brake-cylinder emergency application. 105 110 115

4. A triple valve comprising a casing, valve devices therein, capable of making brake applications, substantially as described, and three springs located at one end of the valve devices and coacting therewith, one spring resisting the movement of the valve devices in one direction and the second and third springs successively resisting movement in the opposite direction. 120

5. A triple valve comprising a casing, valve devices therein, capable of making brake ap-

plications, substantially as described, a stem in connection with the said valve devices, a spring pressing the stem in one direction, a sleeve adapted to be engaged by the stem, a second spring engaging the sleeve and acting in the same direction as the first spring, a second sleeve also adapted to be engaged by the stem, and a third spring engaging the second sleeve and acting oppositely to the two springs first named.

6. In a triple valve, the combination with the main casing and the slide-valve piston, of a hollow rubber cushion with an orifice therein.

7. In a triple valve, the combination with the main casing and the slide-valve piston, of a hollow annular rubber cushion with an orifice therein.

8. In a triple valve, a device for automatically returning the slide to lap position, said device comprising a cap having a cylinder formed therein, a piston working in the cylinder, stems projected oppositely from said piston, one stem serving to engage the slide, a spring encircling the other stem and pressing the piston toward the slide, and means working in the outer end of the cap and engaging the corresponding end of the spring to adjust the tension thereof.

9. A triple valve having a port in the valve-casing establishing communication between the train-line and auxiliary, a feed-valve commanding said communication, a diaphragm actuating the valve, said diaphragm being controlled by auxiliary pressure, a spring back of said diaphragm, acting against the auxiliary pressure, a check in said passage, seating by auxiliary pressure, and a spring-bearing between the check and said feed-valve.

10. A triple valve having a port in the valve-casing establishing communication between the train-line and auxiliary, a feed-valve commanding said communication, and itself controlled by the auxiliary pressure, a check in said passage, seating by auxiliary pressure, and a spring-bearing between the check and said feed-valve.

11. A triple valve comprising a casing having a cylinder and valve-cavity formed therein and also having auxiliary communication from the valve-cavity, and also having a passage from the train-line to the cylinder, a passage from the train-line to the valve-cavity, and a passage from the valve-cavity to the brake-cylinder, a piston in the cylinder, a slide-valve in the valve-cavity, a feed device in the passage from the train-line to the valve-cavity, said feed device being controlled by the auxiliary pressure, and a check in the passage from the train-line to the cylinder, said check

seating against the train-line pressure and having a permanently-open vent therein.

12. A triple valve, having a casing formed with a slide-valve cavity and having a train-line communication extending into the slide-valve cavity, a feed-valve in said train-line communication, the valve-casing also having two ports from the train-line communication direct to the slide-valve cavity, and also having two ports communicating with the slide-valve cavity and with the brake-cylinder connection, a slide-valve having a port opening therein capable of communication with one of the said ports to the brake-cylinder connection and also having a cavity therein capable of connecting one of the ports of the train-line connection with the other of the brake-cylinder ports simultaneously with the communication between the said slide-valve port and brake-cylinder port, a valve commanding the said cavity in the slide-valve and said cavity being also capable of connecting the remaining of the train-line ports with one of the brake-cylinder ports independently of the valve in the cavity, and means for operating the slide-valve.

13. A triple valve, comprising a casing having a train-line, auxiliary and brake cylinder connections, valve devices in the casing, said devices having ports capable of establishing communication between the train-line and brake-cylinder connections to effect a brake application, and also having two additional ports capable each of establishing communication between the auxiliary and brake cylinder respectively to effect service and emergency brake applications, and a cushioning means comprising three elements respectively resisting the aforesaid three movements of the valve devices.

14. A triple valve, comprising a casing, valve devices therein, for the purpose specified, a spring pressing the valve devices in one direction, a sleeve adapted to be engaged by a part of the valve devices, a second spring engaging the sleeve and acting in the same direction as the first spring, a second sleeve also adapted to be engaged by a part of the valve devices, and a third spring engaging the second sleeve and acting oppositely to the two springs first named.

In testimony whereof I have signed my name to this specification in the presence of two subscribing witnesses.

JOHN V. WELLS.
